UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, LONDON, ENGLAND.

MOUNTING FOR AUTOMATIC GUNS.

1,317,862.

Specification of Letters Patent.

Patented Oct. 7, 1919.

Application filed June 21, 1917. Serial No. 176,105.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to Mountings for Automatic Guns, of which the following is a specification.

This invention relates to mountings (particularly tripod mountings) for automatic guns in which the muzzle of the gun during training moves through a comparatively short distance, thus rendering the gun particularly suitable for firing through an aperture in a shield or breastwork.

According to the invention the gun is connected to the crosshead member of the mounting through the intermediary of a rearwardly extending bar or tube which carries the gun in such a position that the axis of the training pivot intersects or approximately intersects the axis of the gun at or near the muzzle end thereof. This bar may be trunnioned at its forward end to the crosshead and may be connected at a point between its ends to the elevating screw or other elevating gear carried by the usual rearward extension of the crosshead.

In order that the said invention may be clearly understood and readily carried into effect we will describe the same more fully with reference to the accompanying drawings, in which:—

Figures 1 and 2 are respectively a side elevation and a plan of a tripod mounting provided with a constructional form of our improvements, the gun having been removed from the mounting in Fig. 2.

Fig. 3 is a view similar to Fig. 1 showing the mounting in its raised or normal firing position,

Fig. 4 is a view similar to Fig. 3 showing a modified form of our improvements, and

Figs. 5 and 6 are views similar to Fig. 3 showing a modified construction of the rearwardly extending bar or tube, the gun and bar being shown in these figures in its alternative positions.

A is the gun, B the crosshead, C the training socket of the mounting, and D the aforesaid rearwardly extending bar or tube

pivotedly connected to the crosshead B by 55 means of a detachable pin d . E is the elevating gear interposed between the bar D and a rearward extension B' of the crosshead.

In Figs. 1 to 3 the bar D is provided with 60 two brackets D' , D'' serving to receive pins d' , d'' by which these brackets are attached to the usual elevating and trunnion lugs D^3 , D^4 on the mechanism casing of the gun. The said bar is also provided with a third 65 bracket D^5 serving to receive a pin d^5 passing through the upper end of the screw of the elevating gear E. It will be obvious that in this construction the muzzle of the gun moves through a relatively short distance during elevation as well as during 70 training. It therefore becomes possible to provide the shield or breastwork behind which the gun is situated with an aperture of small dimensions both as regards height 75 and width.

In Fig. 4 the gun instead of being rigidly connected to the bar D is pivoted thereto by the pin d^2 thereby enabling the gun to be elevated and depressed about this pin relatively to the bar. In this case the part of the bar to the rear of the trunnion lug is bent downward and provided with a clamping device d^x for engaging with a downwardly projecting member D^x to hold the 85 gun at any desired angle of elevation. The member D^x is detachably connected to the elevating lug D^3 by the pin d' .

It will be seen that in both constructional forms of the invention no alteration of the 90 gun itself is necessary nor are any constructional variations in the mounting itself required; it is therefore possible to readily convert any existing gun and mounting by so constructing the aforesaid bar as to suit 95 the particular type of the gun and mounting to be converted. It will also be observed that no training arc is provided for supporting the rear end of the bar.

In the construction shown by Figs. 5 and 100 6 the bar D is so constructed and arranged that in addition to serving the purpose hereinbefore described it will also serve to connect the gun to the crosshead with the gun in the usual firing position in relation to 105 the axis of the training pivot, that is to say with the muzzle of the gun situated a substantial distance in front of the said axis

as shown by Fig. 6. By employing the bar or tube for both positions of the gun, we avoid the liability of the bar becoming mislaid or lost as would be the case if the said bar were removed prior to placing the gun in its firing position in the usual way; furthermore, the time occupied in changing from one position to the other is minimized as it is unnecessary to disconnect the gun 10 from the bar. For this purpose the bar is provided with two downwardly projecting brackets $D'x$ D^{2x} which are arranged immediately beneath and made integral with the brackets D' , D^2 serving for attachment 15 to the elevating and trunnion lugs D^3 , D^4 on the mechanism casing of the gun. Of these downwardly projecting brackets the forward one D^{2x} is made to fit between the cheeks of the crosshead B and to receive the 20 trunnion pin d and the rear one $D'x$ is so constructed as to permit the elevating screw to be connected thereto by the detachable pin d^5 as shown in Fig. 6.

What we claim and desire to secure by 25 Letters Patent of the United States is:—

1. In a mounting for an automatic gun, the combination with the crosshead of the mounting, of a rearwardly extending member pivoted to the crosshead for elevating 30 movements, a rearward extension of said crosshead, elevating gear between said rearward extension and said rearwardly extending member and means for connecting the gun to said member in such a position 35 that the axis of the training pivot intersects or approximately intersects the axis of the gun at or near the muzzle end thereof.

2. In a mounting for an automatic gun, the combination with the crosshead of the 40 mounting, of a rearwardly extending member, means for pivoting said member to the crosshead, means for connecting said mem-

ber to the elevating gear interposed between said crosshead and said member, and means for connecting the gun to said member in 45 such a position that the axis of the training pivot intersects or approximately intersects the axis of the gun at or near the muzzle end thereof.

3. In a mounting for an automatic gun, 50 the combination with the crosshead of the mounting, of a rearwardly extending member connected to the crosshead, means for connecting said member to the elevating gear interposed between the crosshead and 55 said member, means for pivotally connecting the gun to said member in such a position that the axis of the training pivot intersects or approximately intersects the axis of the gun, at or near the muzzle end 60 thereof and so that the gun can be elevated and depressed with respect to said member.

4. In a mounting for an automatic gun, the combination with the crosshead of the mounting, of a rearwardly extending member connected to the crosshead, means for connecting the gun to said member, and means for connecting said member to the crosshead so that the axis of the training pivot intersects or approximately intersects 70 the axis of the gun at or near the muzzle end thereof or so that the gun occupies its usual firing position in relation to the axis of the training pivot namely with the muzzle of the gun situated a substantial distance in front of said axis. 75

In testimony whereof we have hereunto set our signatures.

ARTHUR TREVOR DAWSON.
GEORGE THOMAS BUCKHAM.
